UNITED STATES PATENT OFFICE.

EDGAR F. BELDING, OF FITCHBURG, MASSACHUSETTS.

LEATHER-SKIVING MACHINE.

SPECIFICATION forming part of Letters Patent No. 320,209, dated June 16, 1885.

Application filed March 9, 1885. (No model.)

To all whom it may concern:

Be it known that I, EDGAR F. BELDING, of Fitchburg, county of Worcester, State of Massachusetts, have invented an Improvement in Leather-Skiving Machines, of which the following description, in connection with the accompanying drawings, is a specification, like letters on the drawings representing like parts.

10 This invention has for its object to simplify the construction of that class of skiving-machines more expressly adapted for skiving the edges of shoe tips, counters, and box-toes.

15 My invention being herein shown as an improvement on the form of machine represented in United States Patent No. 272,888, February 27, 1883, to which reference may be had.

20 My invention consists in a novel adjustable guide for holding the pile of blanks; also in the combination, with a feed-roll and knife and a movable support for the blanks to be skived, of a vibrating or reciprocating blank-feeder adapted to successively present the blanks to be skived to the skiving-knife; also in a conical annularly-grooved feed-roll and movable support for the blank, combined with a skiving-knife and a series of vertically movable spring-held pivoted pressers, to operate substantially as will be described.

30 Figure 1 in top view represents a skiving-machine embodying my improvements; Fig. 2, an enlarged detail of the blank holder or guide. Fig. 2^a is a side elevation of the blank-holder; Fig. 3, a front side elevation of my improved machine partially broken out; Fig. 4, a right-hand end elevation of Fig. 3. Fig. 5 is a detail of the feed-roll and its adjustable supports. Fig. 6 is a detail of the plate h, and Fig. 7 a detail of the blank-carrier.

40 The frame-work A, of suitable shape to sustain the working parts, has bearings for the reception of the main shaft A', provided with usual fast and loose pulleys, A² A³. The shaft A' has an attached bevel-gear, A⁴, which 45 engages a bevel-gear, A⁵, fast on the lower end of and rotates the shaft A⁶. The shaft A⁶, next above the gear A⁵, has firmly attached to it the rotating bed B, the hub B' of which is shown in dotted lines, Fig. 3. The bed has 50 attached to it by screws 2, or otherwise, one or more mold-sections, B², containing cavities or depressions 3, of a shape to correspond, sub-

stantially, with that portion of the blank which is to be skived, the cavity herein shown being of suitable shape for a shoe-tip. These mold-sections B² are made removable from the rotating bed in order that sections having recesses of the proper shape may be readily applied to the said bed. The central part of the rotating plate B is cut away at its upper side 55 sufficiently to receive a cam-block, D, which is attached to the plate B by one or more screws 4. This cam-block D has a cam-groove, 5, and at its periphery I have provided the said block with a gear, D', the said gear engaging the teeth of a bevel-gear, a, attached to the shaft a' of the conical feed-roll E, the surface of the latter being provided with a series of annular grooves, 6, the annular projections left at the surface of the said roll being 60 preferably serrated to better engage and feed the blanks. The shaft a' is mounted in ears a² of an arc-shaped head, a³, fitted to slide in an arc-shaped guide, a⁴, the shank a⁵ of which is fitted to slide up and down in the overhanging 65 arm A⁷ of the frame-work A. The shank a⁵ is held in place in the guide by a cap-plate, b, having a shank, b', which is attached to the frame-work by a bolt, b². (Shown in Fig. 1.) At the upper end of shank a⁵ is a pin, c, which, 70 surrounded by a spiral spring, c', enters a central hole in the hollow screw c², held in an ear, c³, of the frame part A⁷, the lower end of the said screw bearing against the upper end of the spring c', the adjustment of the said screw 75 causing the said spring to act with more or less force upon the shank a⁵, and consequently regulate the extent of the yielding pressure of the feed-roll E on the blank, the point to which the said roll may descend being determined 80 by an adjustable stop, c⁵. The rigid part A⁷ of the frame-work has ears 77, which at their lower end serve as bearings for a fulcrum-pin, 8, (see Figs. 3 and 4,) on which is mounted the series of presser-feet f, the latter at their 85 upper ends being bored or slotted to receive the inner ends of the adjustable screw-rods f', each surrounded by a spiral spring, f², each spring acting upon the upper end of a separate presser-foot. The lower ends of the 90 presser-feet, made L-shaped, are extended under the feed-roll E, a part of each foot entering its own annular groove in the said feed-roll. It will be noticed that the shape of the 95 100

presser-feet and the location of the fulcrum-rod 8 is such with relation to the periphery of the feed-roll as to prevent the contact with the said roll of any part of the said presser-feet above the said fulcrum-pin when the arc-shaped head a^3 is being adjusted in the arc-shaped guide a^4 , and it will also be understood that the parts of the presser-feet below the feed-roll and resting on the blanks being carried under the feet press equally and uniformly on the said blanks in all positions of the feed-roll. The point to which a presser-foot may descend under the action of its adjustable spring f^2 is determined by an adjusting device composed of an eccentric-rod, r , having its projecting end squared or otherwise shaped to be engaged by a wrench or key. The journals or ends of the rod r are mounted in the ears 77 of the rigid part A' , and extend from one to the other ear, to serve as a stop for the upper arms of the presser-feet in opposition to the spring f^2 . The overhanging arm A' supports a rock-shaft, G , which is kept from dropping by the nut G' . The shaft G , extended through washers $g\ g$, has at its lower end a hub provided with two arms, $G^2\ G^3$, the arm G^2 being joined by screw 38 to a slotted plate, h , having for its fulcrum the shaft A^6 . The slot 10 (see Fig. 6) in the plate h receives in it a screw, 12, attached to the shank h' , pivoted loosely on the shaft A^6 , the said shank having attached to it the blank-carrier h^2 . (See Fig. 7.) The screw 12 has at its upper end a nut, which may be loosened to permit the screw to be placed at the proper place in the slot 10, to adjust the throw of the carrier h^2 , the said nut being then screwed down to cause the plate h and the shank h' to move in unison. The arm G^3 of the hub of the rock-shaft G has at its end a roller or other stud, which enters the cam groove 5 of the cam D , the rotation of the latter causing the carrier h^2 to be vibrated or reciprocated, the adjustment between the plate h and the shank h' of the carrier h^2 enabling the carrier to operate and engage the pointed rear end of a blank next to be skived just as the center of the concavity or recess 3 in the mold-section B^2 arrives under the center of the pile of blanks, the throw of the carrier h^2 being necessarily adjusted to accommodate different lengths of blanks. The blanks to be skived are cut out to proper shape and placed in a pile, with their ends between uprights or rods of the fingers $m\ m'\ m^2\ m^3$ of the blank-holder H , (shown detached in Fig. 2,) the lowermost blank of the pile of blanks resting directly upon the rotating bed B , which is made to travel under the pile of blanks. The arc-shaped base-plate m^4 of the blank-holder is provided with an ear, m^5 , which is provided with a hole, and the said plate is pivoted on the screw or pin m^6 , held in the ear m^7 of an arm, m^8 , bolted to the bed-plate, the said base-plate being permitted to tip on the said screw m^8 . The periphery of the bed B is cut away to leave a space, 15, and a wall, 16, (see left of Fig. 4,) which, act-

ing against the concaved side of the base-plate m^4 , keeps it on the end of the screw or pivot m^6 . The fingers $m\ m'$ are pivoted by screw 29 to a bracket, 21, made adjustable by a screw, 31, on a second bracket, 22, the slotted foot of which is adjustably attached by screw 23 to the plate m^4 . The screw 29 permits the fingers $m\ m'$ to be separated one from the other to accommodate them to the width of the point of the blank. The fingers $m^2\ m^3$ are adjustable in like manner by screw 17. The screw 31 permits the bracket 21 to be adjusted vertically, to place the lower ends of the upright rods of the fingers $m\ m'$ as close to the bed B as possible without touching it, so that the said rods will prevent the lowermost blank of the pile from being carried forward with the bed, except just at the proper time, when the rods are lifted sufficiently above the bed B to permit the blank to pass under them. The rods of the fingers $m\ m'\ m^2$ and m^3 are lifted by the cam 33, attached to the bed B by the screw 34, the said cam striking the short end of the plate m^4 and tipping it up on the screw m^6 . The plate m^4 has a slot, 25, which, together with the screw 20, enables the bracket 19 to be adjusted on the plate m^4 , to place the fingers at the proper distance apart for the length of the blank. The front end of the carrier h^2 is recessed (see Figs. 1 and 7) to embrace the point of the lowermost blank of the pile of blanks just as the recess 3 coincides in position with the blank, and as the carrier starts to carry the blank forward with the bed B , the blank being in the concavity 3, the cam 33 lifts the plate m^4 , and permits the leading corner of the blank to pass the rods of the fingers $m\ m'$. The carrier continues to act upon the rear corner of the blank until the leading corner thereof is entered under and caught by the feeding-roll E , when the carrier is thrown back by the cam 5. The notch in the carrier h^2 is shaped to embrace the corner and part of the body of the blank, so that the latter is prevented from being displaced sidewise. The skiving-knife n is attached by screws $n'\ n'$ to a bridge-piece, n^2 , held in place by the screws $n^3\ n^4$, the beveled edge of the knife being presented diagonally to the blank, to skive all that part of the same outside of the concavity 3.

I claim—

1. In a skiving-machine, a movable bed and attached mold-section, and a skiving-knife, and an annularly-grooved conical feed-roller, and the arc-shaped head, and the vertically-movable guide in which it is adjustable, combined with a series of spring-actuated presser-feet, f , pivoted upon a rod, 8, parallel with the top of the bed, the lower ends of the said presser-feet being extended under the feed-roller and in its grooves, the vertical parts of the pressers above the fulcrum-rod 8 being entirely outside the periphery of and free from the feed-roller, substantially as described.

2. The movable bed, its attached mold-section, the conical feed-roller, the arc-shaped head provided with ears to hold the shaft of

the feed-roll, the arc-shaped guide in which the said head is made adjustable, and a skiving-knife, combined with a series of pressers extended under the feed-roll, substantially as described.

5. In a skiving-machine, an annularly-grooved feed-roll and a series of spring-actuated pressers, *f*, combined with an eccentric-rod, *g*, to adjust the position to which the said pressers may descend, substantially as described.

10. In a skiving-machine, a movable bed, combined with a blank-holder having two sets of fingers provided with rods or standards to act upon the edges of the forms to be skived, substantially as described.

15. In a skiving-machine, a movable bed, *B*, and a pivoted blank-holder having adjustable fingers provided with rods, combined with a cam or projection to turn the said holder on its pivot and raise the rods when the feeding end of the blank is to be pushed out from the holder, substantially as described.

20. In a skiving-machine, a blank-holder composed of a plate, *m*⁴, adjustable brackets 19 and 22, and adjustable fingers *m m' m² m³*, to operate substantially as described.

25. In a skiving-machine, a bed to receive upon it the article to be skived and a cam-

30. plate, *D*, combined with the vibrating or reciprocating blank-carrier and with means, substantially as described, to operate the said blank-carrier.

8. The bed and blank-holder, combined with the vibrating blank-carrier, slotted or recessed 35 at its acting end to embrace the rear end of the blank, substantially as described.

9. In a skiving-machine, the bed, its mold-section, and the cam *D*, combined with the arms *G² G³*, link *G⁴*, adjustable plate *h*, and the 40 vibrating carrier *h²*, the shank of the latter being provided with a set-screw to enter the slot of the plate *h* and adjust the throw of the said carrier, substantially as described.

10. The blank-holder, the mold-section, and 45 the independent vibrating carrier, combined with a feed-roll and presser-feet to grasp the leading end of the blank to be skived as the latter is presented to the said feed-roller and pressers by the carrier and mold-section, substantially as described.

In testimony whereof I have signed my name to this specification in the presence of two subscribing witnesses.

EDGAR F. BELDING.
